DESIGN FOR AN EDIBLE CONTAINER FOR ICE CREAM AND OTHER CONFECTIONS

John W. Hose, Kew Gardens, N. Y.

Application January 3, 1934, Serial No. 50,296

Term of patent 3½ years

To all whom it may concern:

Be it known that I, JOHN W. HOSE, a citizen of the United States and resident of Kew Gardens, in the Borough and county of Queens, in the city and State of New York, have invented a new, original, and ornamental Design for Edible Containers for Ice Cream and Other Confections, of which the following is a specification, reference being had to the accompanying drawing forming a part hereof.

In the drawing, Fig. 1 is a perspective view of an edible container for ice cream and other confections showing my new design;

Fig. 2 is a side elevation thereof; and

Fig. 3 is a bottom plan view thereof.

I claim:

The ornamental design for an edible container for ice cream and other confections, as shown.

JOHN W. HOSE.
